Des. 612

Winslow Ames, of Nashua, N. H.

Assignor to

Hartshorn, Ames, & Co. of Boston, Mass.

Letters Patent No. 612. Dated Dec. 20th, 1853.

The schedule referred to in these Letters Patent, and making part of the same,

To all persons to whom these presents shall come:

Be it known that I, Winslow Ames, of Nashua in the County of Hillsborough, and State of New Hampshire, have invented or produced a new and ornamental Design for a Cooking Stove; and I do hereby declare that the same is fully represented in the accompanying drawings, of which Figure 1 represents a perspective elevation of the stove, Figure 2, a vertical section of the front plate, cornice base moulding, hearth plate and ash box, the said section being taken through the middle of ^{base} two of the front fire doors; Figure 3. is a vertical section of the side plate, and cornice, said section being taken through the middle of the two lesser side doors.

The ornamental character of the base and cornice, or the combination of mouldings constituting the same, is defined by the sections in Figures 2 and 3. The side plate is ornamented just above the base plate by a series of spear heads, and below the cornice by a fringe of Gothic archwork terminating in diamonds and tassellated pendants arranged alternately as seen in the drawings.

The ornamental character of the doors on both the front side plates is exhibited in the drawings with all the accuracy of detail necessary to enable a pattern maker of ordinary skill to understand and carry out the same in their practical development.

I claim as my invention, the ornamental design of the side plate of the body of the stove, and of each of the larger and smaller doors of either of the front or side plates, as exhibited in the drawings.

In testimony whereof, I have hereunto set my signature,
this sixth day of December, A. D. 1853.

Witnesses;

R. H. Eddy, }
F. P. Hale, Jr. }
